UNITED STATES PATENT OFFICE.

SAMUEL W. RAYMOND, OF ADRIAN, MICHIGAN.

SERVICE STATION.

1,388,893.

Specification of Letters Patent. Patented Aug. 30, 1921.

Application filed July 9, 1917. Serial No. 179,351.

To all whom it may concern:

Be it known that I, SAMUEL W. RAYMOND, a citizen of the United States of America, residing at Adrian, in the county of Lenawee and State of Michigan, have invented certain new and useful Improvements in Service Stations, of which the following is a specification, reference being had therein to the accompanying drawings.

10 This invention relates to a service station, and has special reference to a dispensing machine or apparatus adapted for supplying automobiles with gasoline or kerosene for an engine, with air for inflating the tires, 15 with oil for lubrication purposes and with water for the radiator.

The primary object of my invention is to provide a service station of the above type that will include simple and effective means 20 for supplying fuel, in contradistinction to the usual hand operated pump now employed. This object is attained by using air under pressure, and in resorting to such means for lifting fuel to a height where it 25 may flow by gravity to the tank of an automobile, I use the means in a manner that conforms to the requirements of the Underwriters' Association, thus insuring safety about the service station.

30 Another object of my invention is to provide a service station including a transparent reservoir in which fuel in predetermined quantities may be placed and observed.

A further object of my invention is to provide 35 a service station of novel design that embodies certain features that will herein-after appear as the invention is better understood, and reference will now be had to the drawing, showing a vertical sectional view of the service station in accordance 40 with my invention.

In the drawing, 1 denotes a base having a pedestal 2 and said pedestal is provided with a suitable door 3 whereby easy access 45 can be had to the interior of the pedestal.

On the top of the pedestal 2 is a transparent casing 4 provided with a suitable cap 5 having an electric lamp 6 and suitable lead-in wires or cables 7 are adapted to supply 50 electricity so that the lamp 6 as well as other lamps in or about the station may be illuminated.

Buried in the ground adjacent the station and at the necessary depth for safety pur-

poses, is a main fuel tank 8 having suitable 55 capped filling pipe 9 which permits of gasoline or other fuel being placed in the main tank. Adjacent the main tank 8 is an auxiliary tank 10, lower in the ground than the main tank 8, and extending into the auxiliary tank 10 and in close proximity to the bottom thereof is a reservoir pipe 11 extending upwardly through the pedestal 2 and connected to the base 12 of a reservoir 13 suitably supported or mounted in the 60 casing 4. The reservoir 13 is preferably made of glass or provided with a sight opening, so that the quantity of fuel therein may be readily observed. The reservoir pipe 11 is provided with a shut off valve 14 having 65 an operating handle or lever 15 and a crank 16. This valve may be manually adjusted by opening a door 17 of the casing 4.

Extending through the reservoir 13 is an 70 overflow and vent pipe 18 and the lower end of said pipe is connected to the filling pipe 9 of the main tank 8. The upper end of the pipe 18 is opened and within the reservoir 13 said pipe has an opening 19, adjacent the top of the reservoir, which limits the 75 capacity of the reservoir 13, as fuel cannot rise in the reservoir above the opening 19 without flowing back through the pipe 18 into the main tank 8. The opening 19 also permits of air entering the top of the reservoir 80 and gases or fumes escaping therefrom. That portion of the pipe 18 within the reservoir 13 may be graduated or the walls of the reservoir may be similarly marked or provided with indicia so that a desired quantity of fuel may be obtained.

The top of the main tank 8 has a siphonic 85 connection 20 with the reservoir pipe 11 adjacent the auxiliary tank 10, so that a quantity of fuel will be maintained in the auxiliary tank independent of the tank 8. That 90 end of the siphonic connection 20 in the tank 8, has a check valve 35 of a conventional form preventing back flow into said tank. The auxiliary tank has the top thereof connected to an air pipe 21 extending upwardly 95 through the pedestal 2 in proximity to the reservoir 13. The upper end of the air pipe 21 is provided with a two-way valve 22 having a crank 23 connected by a link 24 to the 100 crank 16 of the valve 14, permitting of said valves being operated in synchronism. The valve 22 is connected to an air supply pipe 105

25 adapted to supply air under pressure, to the valve 22 and the auxiliary tank 10. The pipe 25 is provided with a shut off valve 26, a safety valve 27, a gage connection 28, and 5 a reduction valve 29. The gage connection 28 extends in proximity to the valve 22 and has a conventional form of gage 30 so that the pressure of air may be ascertained. The reduction valve 29 may not be necessary, but 10 is used when the air pressure is high, and needs reducing as a safety factor.

The valve 22 has a connection 31 with a vent pipe 32, said pipe communicating with the top of the main tank 8 and extending 15 to the top of the service station to communicate with the atmosphere. The reservoir pipe 11, above the valve 14, has a branch provided with a shut-off valve 33 and connected to said valve is a hose 34 or other 20 conduit, so that fuel from the reservoir 13 may be conducted, by gravity, to the fuel tank of an automobile.

Extending into the pedestal 2 of the station are air, water and oil supply pipes, provided 25 with suitable faucets in proximity to the door 3 of the pedestal, so that an automobile may obtain water for the radiator of the engine, oil for lubricant purposes, and air for inflating the tires.

30 To prime the siphonic connection 20, the main tank 8 can be filled until the auxiliary tank 10, the siphonic connection 20 and the lower ends of the pipes 11 and 21 are filled with fuel.

35 In operation, I will assume that three gallons of gasoline are to be obtained from the station and that the hose 34 has been placed in communication with an automobile tank and the valve 33 closed. When the attendant 40 of the station shifts the lever 15 of the valve 14 to open said valve, placing the reservoir 13 in communication with the auxiliary tank 10, the valve 22 is also adjusted to close the branch connection 31 and place 45 the air supply pipe 25 in communication with the air pipe 21. The pressure of air on the gasoline in the auxiliary tank 10 will force the gasoline upwardly through the reservoir pipe 11 into the reservoir 13, 50 there being a greater quantity of gasoline in the auxiliary tank 10 than what can be held in the reservoir 13. As the gasoline rises within the reservoir 13 and reaches a graduation of three gallons, then the attendant 55 of the station closes the valve 14 and in so doing adjusts the valve 22 to shut off the supply of air thereto and establish communication between the pipe 21 and the branch connection 31, so that the auxiliary tank 10 has a vent to the atmosphere through the pipe 21, valve 22, connection 31 and air vent pipe 32. The valve 33

can now be opened and three gallons of gasoline withdrawn from the reservoir.

From the foregoing, it will be observed 65 that the main and auxiliary tanks have vents to the atmosphere and consequently fumes or gases cannot collect therein and become a dangerous factor. It is also apparent that there is no pressure on the gasoline in either 70 tank when the station is not in use, and that air under pressure is only conducted to the small quantity of gasoline in the auxiliary tank, when gasoline is to be dispensed, and not to the main tank, so large quantities of 75 gasoline can be readily stored in the main tank. These safety features are requirements of the Underwriters' Association and permit of the service station being used with perfect safety and with much satisfaction 80 and convenience to automobileists, as all operating necessities are at hand and each automobile will know the exact quantity of the fuel before purchasing the same.

What I claim is:—

85 In a fuel dispensing apparatus, a reservoir, a main fuel tank provided with an air vent pipe, an overflow pipe for said reservoir and having a side opening communicating with said reservoir, said overflow pipe 90 having its upper end extending out of the reservoir and open to the atmosphere and its lower end communicating with said main fuel tank, an auxiliary fuel tank at a level below said main fuel tank and separate 95 therefrom, a pipe extending from the bottom of said auxiliary fuel tank to the bottom of said reservoir, a fuel valve carried by said pipe, a siphonic connection between said main fuel tank and said pipe so that the 100 fuel may be siphoned from said main tank into said auxiliary fuel tank, an air supply pipe adapted to communicate with said auxiliary fuel tank, an air valve carried by said air supply pipe adapted to either admit air 105 to said auxiliary fuel tank or place said tank in communication with the atmosphere, and a connection between said air valve and said fuel valve so that said valves may be operated in synchronism, said valves being arranged so that when air pressure is in said auxiliary fuel tank said reservoir 110 communicates with said auxiliary fuel tank, and when said fuel valve is closed said air valve establishes communication between said auxiliary fuel tank and the air vent pipe of said 115 main fuel tank.

In testimony whereof I affix my signature in the presence of two witnesses.

SAMUEL W. RAYMOND.
